UNITED STATES PATENT OFFICE.

CHARLES L. PEIRCE, JR., OF PITTSBURGH, PENNSYLVANIA, ASSIGNOR TO HUBBARD & CO., OF PITTSBURGH, PENNSYLVANIA, A CORPORATION OF PENNSYLVANIA.

INSULATOR-BRACKET.

1,007,138.

Specification of Letters Patent. Patented Oct. 31, 1911.

Application filed October 26, 1910. Serial No. 589,091.

To all whom it may concern:

Be it known that I, CHARLES L. PEIRCE, Jr., a resident of Pittsburgh, county of Allegheny, and State of Pennsylvania, have invented certain new and useful Improvements in Insulator-Brackets, of which the following is a full, clear, and precise specification.

My invention relates to insulator brackets, and particularly to such brackets constructed entirely of metal.

The more modern insulator brackets usually comprise a narrow back piece to which several insulator supporting members are fastened, preferably by being riveted thereto, and bolt holes are provided in the back piece for securing said piece to a support. The back piece and brackets are usually bent up and formed of stock material, such as channel iron. It has been found in practice, however, that the narrow back piece will not give proper bearing on the wall or other support when wires pull off from the side of the support. Another objection to this form of bracket is that, owing to the position of the bolt holes some distance either above or below the point of strain of wires pulling from the insulators, the back piece has a tendency to bend at the bolt holes. The strength and stability of the insulator is, therefore, greatly reduced.

The object of my invention is, therefore, to devise construction and arrangement for overcoming these defects, yet at the same time to produce an insulator bracket which will cost no more to manufacture than these prior insulators referred to, and whose strength, stability and general efficiency will be greater.

My invention will be clearly understood from the following specification and by reference to the accompanying drawings, in which several embodiments for carrying out my invention are described and shown.

In the drawing—Figure 1 is a perspective view, showing one form of back piece having a single longitudinal corrugation or strengthening rib which fits inside the channel supports, Fig. 2 is a cross-sectional view taken on plane 2—2, Fig. 1, Fig. 3 is a perspective view of a bracket, in which the back piece has two longitudinal corrugations or ribs, between which the supporting members fit, Fig. 4 is a cross-sectional view taken on plane 4—4, Fig. 3, Fig. 5 is a perspective

view of a bracket, showing a back piece having a central longitudinal corrugation or ridge and openings through which the brackets can pass to engage within the corrugation or rib, Fig. 6 is a sectional view taken on plane 6—6, Fig. 5, Fig. 7 is a perspective view, in which individual corrugated straps are used to receive both the back piece and the supporting members, Fig. 8 is a sectional view taken on plane 8—8, Fig. 7, Fig. 9 is a perspective view, showing a slight modification over the form shown in Fig. 7, and Fig. 10 is a sectional view taken on plane 10—10, Fig. 9.

In the modified forms the insulator supporting units S are each bent up from channel iron or steel, which can be bought on the market in any size. Each supporting unit is preferably bent to U-shape with the flat side of the channel iron on the inside and the limbs thereof on the outside. The outer end 11 of each supporting unit has secured thereto a suitable insulator supporting attachment such as a spiral spring 12 forming the thread for receiving the glass insulator, the other end 13 of the supporting unit having a rivet hole 14 whereby the unit may be secured to a back piece, this rivet hole being preferably in the line of strain of a wire pulling from the insulator.

Referring now to Figs. 1 and 2, the back piece or unit supporting member 15 is in the form of a comparatively wide plate or strip of sheet metal having a central longitudinal corrugation or ridge 16 raised therefrom, this corrugation or ridge being preferably of substantially U-cross section to fit between the channel limbs of the ends 13' of the insulator carrying units. Each back piece may carry any number of units, which are suitably spaced thereon, and the front face of the corrugation or rib is provided with holes 17 to register with the holes 14 in the insulator carrying units to receive rivets or bolts 18 whereby the insulator carrying units may be securely fastened to the back piece. The width of the corrugation or ridge 16 is substantially the same as the distance between the sides or legs 13' of the ends 13 of the insulator supporting units, so that when the units are riveted or bolted to the corrugation these legs will intimately engage with the corrugation sides and will securely lock the units against lateral movement or displacement or against turning.

Adjacent each hole 17 in the corrugation are the bolt holes 19 punched in the plate 15 for accomodaitng bolts or lag screws for fastening the plate to a support. Each 5 set of openings 14—19 are in the plane of the strain of wire pulling from the corresponding insulator, and the entire strain will therefore be taken up by the rivets 18 and by the bolts or screws passing through the 10 holes 19. This is the most efficient arrangement, as, if the holes 19 were either above or below the respective rivets 18, the pull of the wires would be transmitted first to the 15 plate and then to the bolts which secure the plate to a support, this introducing a leverage action on the plate, which would tend to buckle or bend it. The plate with the single corrugation can be rolled very readily and cheaply.

20 In the form of Figs. 3 and 4 we have substantially the same features as in the form of Figs. 1 and 2, with the exception that instead of one single corrugation, two corrugations 20 and 21 extend longitudinally 25 and parallelly from the plate 22, and the legs 13' of the ends 13 of the insulator carrying units engage between these corrugations instead of receiving the single corrugation. The positions of the rivet holes 14 and bolt holes 19 with reference to the line 30 of strain are exactly the same as in the form of Figs. 1 and 2. In this modified form the distance between the corrugations 20 and 21 is such that the ends 13 of the insulator supporting units will be intimately received 35 between the corrugations, so that when the insulator supporting units are riveted in place they will be rigidly locked against lateral or rotational displacement.

40 In the modification illustrated in Figs. 5 and 6 the back piece 23 has a single central longitudinal corrugation or ridge 24, which forms a channel 25 along the rear of the back piece, and the width of this channel 45 is substantially equal to the width of the ends 13 of the insulator supporting units. At suitable intervals the front wall of the corrugation has openings 26 through which the ends 13 can be inserted to bring these 50 ends into the channel 25, whereafter rivets are applied at the registering holes 17 and 14 to secure the units in place, the engagement of the ends 13 in the channel 25 preventing any lateral or rotational displacement 55 of the units. The bolt or screw holes 19 are provided adjacent the rivet holes in the same manner as in the foregoing modifications, so that the bolts and rivets will be in the plane of strain on wires held to 60 the insulators.

In the modifications of Figs. 7 and 8 I accomplish the same features as in the foregoing forms. However, instead of having a continuous wide back piece I use a narrow 65 back piece 27 preferably in the form of

channel iron or steel. To the flat face of this channel iron back piece I apply the ends 13 of the insulator supporting units, as shown, and to secure the insulating units to the back piece in this position I provide 70 straps 28, whose cross-section is substantially that of the back pieces illustrated in Figs. 1, 2, 5 and 6. The corrugated or deflected central part 28^a of the strap has the same width as the ends 13 and the back piece 27, and the 75 depth thereof is sufficient to receive both the end 13 and the back piece engaged thereby. The outer wall of the deflected part has a rivet hole 28^b for registering with the rivet hole 14 in the insulator supporting unit and the rivet hole 27^a in the back piece. Thus, when a rivet is applied through the three 80 rivet holes the strap, insulator supporting unit, and back piece are rigidly clamped and secured together, and the insulator supporting unit is locked against lateral or rotational displacement relative to the back piece. The wing or foot parts 28^c of each strap have bolt holes 28^d by means of which 85 the entire structure can be secured to a support, and the bolt holes and rivet hole of each strap are in the plane of strain of wires held by the corresponding insulator.

In Figs. 9 and 10 the arrangement is slightly different from that shown in Figs. 95 7 and 8, in that the ends 13 of the insulator supporting units, instead of being of the same width as the back piece, are wider, so that the legs 13' will receive the back piece, and the deflected part of the strap is also 100 wider to receive the ends 13. Otherwise, however, the arrangement and operation is exactly the same as in the form of Figs. 7 and 8.

By means of my improved features of 105 construction and arrangement brackets are provided in which the insulator supporting units are suspended from the back member by a single rivet, and the engagement of the units with the back member is such that lateral and rotational displacement are entirely 110 prevented. The back member is comparatively wide and offers a secure base and support against side pull of wires. The various rivets and bolt holes are in the line of 115 the strain and directly receive the strain, so that no buckling, bending or twisting of the supporting blade can result. The stock for the various parts of the brackets can be very readily and cheaply rolled and cut into 120 proper lengths.

I do not desire to be limited to the precise forms and arrangements shown and described, as other modifications are possible which would still come within the scope of 125 my invention, and I therefore desire to secure the following claims by Letters Patent:

1. In an insulator bracket, the combination of a comparatively wide back piece or 130

base having a corrugated section, and an insulator supporting unit riveted to said back piece or base and engaging with said corrugated section to be locked against lateral or rotational displacement.

5. 2. In an insulator bracket, the combination of a back piece or base provided with longitudinal corrugation walls, an insulator supporting unit, and a single rivet supporting said unit from said back piece or base, said unit being engaged by the corrugation walls to be locked thereby against lateral or rotational displacement with relation to the back piece or base.

10. 3. In an insulator bracket, the combination of a comparatively wide sheet metal supporting strip deflected along a longitudinal area to form side surfaces, an insulator supporting unit formed of channel iron, and a single rivet connecting said unit with said supporting strip, sections of the limbs of the channel iron forming the unit engaging with said side surfaces on the supporting strip whereby said unit is locked against lateral or rotational displacement on said strip.

15. 4. In an insulator bracket, a supporting strip stamped integral from sheet metal and ridged along a longitudinal area to form side surfaces, insulator supporting units each in the form of a U-frame bent from a piece of channel iron, and a single rivet securing each unit to the supporting strip, the flanges of the channel iron units engaging with said side surfaces formed on the supporting strip whereby the units are locked against lateral displacement and rotational displacement about the rivets.

20. 5. In an insulator bracket, the combination of a back piece having longitudinal side surfaces, and insulator supporting units secured to said back piece to engage with said side surfaces to be thereby locked against lateral and rotational displacement.

25. 6. In an insulator bracket, the combination of a sheet metal back piece having longitudinal side surfaces, and insulator sup-

porting units formed of pieces of channel iron riveted to the back piece to intimately engage with the side surfaces thereof to be thereby locked against lateral or rotational displacement.

30. 7. In an insulator bracket, the combination of a back strip having side surfaces, an insulator supporting unit formed of a piece of channel iron, the channel sides of said unit engaging with the side surfaces of the back strip, and a single rivet for supporting the unit from the back strip and for maintaining engagement of the channel sides with the side surfaces, whereby said unit is locked against lateral or rotational displacement relative to the back piece, said back piece having bolt holes adjacent said rivet and said bolt holes and rivet being in the line of strain of wires supported from said unit.

35. 8. In an insulator bracket, the combination of a back strip having side surfaces, an insulator supporting unit formed of a piece of channel iron whose channel sides engage with the side surfaces of the back strip, and means for securing said unit to said strip, the engagement of the channel sides of the unit with the side surfaces of the strip preventing lateral or rotational displacement of the unit with reference to the strip.

40. 9. In an insulator bracket, the combination of a plate deflected at its middle to form a channel, an insulator supporting unit formed of a piece of channel iron and having one end inserted in said channel with its flange sides engaging against the channel sides whereby the unit is locked against lateral and rotational displacement, and a rivet passing through said plate and the unit to lock said unit within the channel.

In witness whereof, I hereunto subscribe my name this 19th day of October, A. D. 1910.
